UNITED STATES PATENT OFFICE.

ELMER A. SPERRY, OF NEW YORK, N. Y.

INTERNAL-COMBUSTION ENGINE.

1,194,889.

Specification of Letters Patent. Patented Aug. 15, 1916.

Original application filed December 10, 1892, Serial No. 454,752. Divided and this application filed January 7, 1915. Serial No. 962.

To all whom it may concern:

Be it known that I, ELMER A. SPERRY, a citizen of the United States, residing at borough Brooklyn, New York city, in the county of Kings and State of New York, have invented certain new and useful Improvements in Internal-Combustion Engines, of which the following is a specification.

10 This invention relates to internal combustion engines; and it is concerned more particularly with devices for supplying combustible mixture to the combustion cylinders of such engines.

15 The invention hereinafter set forth is disclosed in my application Serial No. 454,752, filed Dec. 10, 1892, of which the present application is a division.

Although the engine hereinafter described 20 may be designed to operate with any suitable liquid or gaseous fuel, yet the arrangement of parts here shown for forming and supplying combustible mixture to the engine contemplates more especially the use of a 25 liquid fuel, such as gasoline or the like.

Prior to my invention the employment of such fuel has offered certain difficulties and disadvantages which the present invention overcomes. Thus, it has been found very 30 difficult to properly regulate the flow of gasoline, for example, from a supply tank to the point at which it is to be mixed in finely divided form, such as vapor, with air for use in the engine; and also to obtain a thorough 35 and homogeneous mixture of fuel and air in proper proportions suitable for use over a wide range of engine speeds and under varying conditions of operation. Moreover, in using gasoline, the odor of the fuel has 40 been an objectionable and heretofore unavoidable feature of engines employing it.

According to the present invention I control the flow of liquid fuel to the feed orifice or nozzle by interposing in the piping connections between the main supply tank and said nozzle, a device arranged to maintain a relatively small supply of fuel at a constant level somewhat below the level of the nozzle outlet. Liquid fuel is supplied under 45 pressure from the supply tank to said device which operates automatically to permit flow

of fuel in amount sufficient to maintain the predetermined level of the intermediate supply, and to cut off flow of fuel in excess of such amount. The flow of fuel is thus always proportional to the requirements of the engine and is under positive control at all times.

In order to obtain a thorough and easily controllable mixture of fuel with air, I make use of separate currents of air which are caused to flow by the same impelling means, that is, by a common impelling means, in such manner that one of said currents, which may be termed the primary current, entrains and atomizes fuel from the supply nozzle, while the other or secondary air current serves to dilute the rich mixture first formed, thereby giving a final mixture of the proper composition to use in the engine. Preferably both air supplies are operated or maintained at superatmospheric pressure.

The objectionable odor heretofore usually characterizing engines using volatile fuel may be avoided according to the present invention by inclosing in a hood or canopy such parts of the fuel conducting and controlling system as are more or less liable to leak, and by causing air to pass through said hood or canopy to the intake of the engine, whereby all odor, fumes, etc., due to fuel leakage are removed and whatever heat value they contain is utilized in the engine. These and other advantageous features of the invention will appear more fully as the description proceeds, and will be pointed out in the claims.

The accompanying drawings illustrate by way of example one form of internal combustion engine in which the principles of my invention may be embodied.

In these drawings: Figure 1 is a plan view of the engine, partly in section; Fig. 2 is a detail; Fig. 3 is a side elevation, partly in section; Fig. 4 is a cross sectional view showing more or less diagrammatically the relative position of the engine cylinders, etc.; Fig. 5 shows diagrammatically the fuel supply tank and piping connections; Fig. 6 is a detail view, partly in section, of a suitable constant level device, and a fume collecting hood or canopy surrounding the

same; Fig. 7 is a detail view of the fuel supply nozzle and its controlling valve; and Fig. 8 shows diagrammatically an assemblage of the fuel supplying and controlling devices with the engine proper.

For the sake of example, and not intending thereby to limit the application of the various features of the invention to any particular type of internal combustion engine, I have illustrated the invention as embodied in the present instance in a compound engine. The specific engine here chosen for the purpose of explaining the invention in one of its practical forms, is arranged to take a precompressed charge, formed by separately compressing air and then introducing fuel thereinto at or just prior to entry into the engine intake. The general arrangement of engine parts will be briefly described first, and the fuel feeding devices will then be considered in detail.

Referring more particularly to Figs. 1 to 4, the engine here shown comprises two high pressure or combustion cylinders D³ and D⁴ surrounded by a casing C'', said cylinders being side by side and in tandem with the much larger cylinder inclosed by casing C', this larger cylinder serving both as a low pressure or expansion cylinder, and also as an air compressor cylinder as will subsequently appear. The joint between the two casings is shown at D'', the parts being held together by ears, bolts, or any other suitable means. The cylinders may be water jacketed as at F'' G, cooling fluid entering below through pipe H valved at H', and leaving through G'. The cylinders are closed by suitable heads I.

The high pressure pistons D and D' are hollow and are closed at the right hand ends, while at the left they open to the low pressure piston C, to which they may be flexibly connected by means of rods E and ball and socket connections, which latter are held in position by means of clamps E' provided with bolts E''. The low pressure piston C is also hollow or cup shaped, being closed at the left to present a low pressure working face, the other or inner face toward the right constituting an air compressor face. Piston rods B'' connect the piston C to cross head B', to which is secured pitman B, which in turn is arranged to drive crank shaft A carrying large fly wheel A' and suitably supported by engine base A. Suitable provision is made in casing C'' for accommodating the moving piston rods B'', such provision being indicated at I' in Fig. 4.

L is the fuel intake valve for cylinder D³, and igniting device O', heated by burner O⁴, communicates with the intake end of D³ by way of passages in a removable cap member O⁵. Passages J, controlled by valves J' serve to conduct hot combustion gases at relatively high pressure from the forward ends

of the high pressure cylinders D³ and D⁴ to the expansion chamber C³ at the rear of the low pressure piston. Each of the valves J' is held to its seat by a spring J⁶ pressing against the head J⁶' of stem J⁶. These valves are arranged to open alternately, this operation being effected and properly timed in accordance with the four-cycle operation of the engine by means of suitable valve actuating mechanism (Fig. 1), said mechanism comprising in this instance levers a'' pivoted at a⁴. One end of each lever engages one of the heads J⁶, while the other end carries a roller a' lying in the path of a wedge-shaped contactor or cam S which moves longitudinally with a member A³, which latter is reciprocated by means of a suitable eccentric A⁴ acting through eccentric rod A⁵ on pin A⁶ which is carried by A³. The cam S is mounted in a dovetailed groove S' in member A³, and is suitably moved transversely to A³ by suitable mechanism (not shown) in such manner that the levers A² are alternately actuated to open valves J' at the proper intervals.

Exhaust from the low pressure or expansion cylinder passes into exhaust conduit K through a suitable port controlled by a valve K' (Fig. 2) normally held to its seat by a spring K'' and opened at proper intervals by means of a rod A⁸ secured to arm A⁷ of the reciprocating member A³, the valve rod being suitably guided as at A⁹.

The space I'' to the right of the low pressure piston constitutes an air compressor chamber having an air intake N valved at N', and a compressed air outlet valved at M. In the specific engine here illustrated, the air is caused to follow a sinuous course as it passes from the intake to the outlet of the compressor, this course being indicated by arrows in Fig. 1. The air is partly guided in its course by means of diaphragms or baffles F arranged within the hollow pistons D and D' as indicated in Figs. 1 and 4. The arrangement shown affords a means of internally cooling the high pressure pistons.

As before stated, air for the combustible charge is separately compressed before being mixed with the fuel. To this end, the discharge valve M of the pump or compressor cylinder is connected to a tank M', Fig. 5, by a pipe M''. An escape valve M³ is connected to this pipe or to the tank as shown. A spring M⁴ serves to regulate the pressure within the tank M', as will be readily understood. In this instance, the tank M' also serves as a fuel supply tank, being partly filled with gasoline or other liquid fuel as shown in Figs. 5 and 8. Leading from the tank M' are two air pipes, O and O', the pipe O connecting with the space above the fluid level, and pipe O' dipping into the fluid, which latter is forced

through pipe O' by the air pressure above its surface. The pipes O and O' conduct air and gasoline respectively to a fuel induction device or atomizer O'' (Fig. 7) which is located within the compressed air conduit K³, which conduit branches from compressed air pipe M'' and leads to the fuel intake of the engine. Most advantageously this air induction passage or pipe K³ is so arranged that air passing therethrough on its way to the engine intake is preheated by the exhaust gases leaving the engine through exhaust pipe K. As here shown, said exhaust pipe surrounds a considerable length of air pipe K³. In the specific embodiment here illustrated, the gasoline pipe O' leads to the nozzle or atomizer by way of a flow controlling device, which will be more fully hereinafter described. The fuel may, however, be conducted to the device O'' directly from the tank M'. In either case, the sucking action of the air rushing past the nozzle when drawn into the combustion chambers by the receding piston in either of the said chambers D³ or D⁴ draws a certain quantity of fuel through the valve-controlled aperture whenever valve P, hereinafter described, will permit. Branch pipes X and Y lead from pipes O and O' respectively, to the burner O⁴.

It is to be noted that the air pipe O enters the gasoline pipe O' in the vicinity of the nozzle or atomizer, terminating within the pipe O' as shown. The outlet aperture of the gasoline pipe is just beyond the end of the air pipe and is provided with the shut-off valve P, which is pivoted at P' within duct K³ between the nozzle and the engine, and which has a foot P⁰ adapted, upon suitable actuation of the valve, to swing across the nozzle outlet and reduce feed of fuel therefrom to a greater or less extent, thus affording variable obstruction to the flow of combustible mixture to the combustion chamber. The valve P may be automatically operated from any governing element, as for example by the ordinary hit-or-miss mechanism here shown. In this instance, such mechanism comprises a finger P³ carried by a governor consisting of weight P⁴ pivoted at P⁵ to a suitable moving part A¹⁰ of the engine, said part A¹⁰ being reciprocated by means to be hereinafter described. The finger P³ is arranged to engage a notch P'' in a controlling arm which extends upwardly from the valve P and outside of the pipe K³. When the finger P³ moves forward in engagement with the notch P'', the valve is opened as indicated in dotted lines in Fig. 7. It is desirable in the present arrangement that the opening should obtain through about one-half of the stroke of the engine. A spring shown at P⁷ serves to return the valve P to its seat when released by finger P³. At sufficiently high speeds, the

finger P³ misses the notch P'', thus permitting the valve P to partially or wholly cut off the fuel supply, thus reducing the richness of the mixture passing to the engine intake as may be required. It is apparent that the feed of fuel from the nozzle may be further regulated and controlled by suitable adjustment of the throttle g. I have found that for the best results the throttle g should be as near the outlet aperture as possible, especially for a duplex engine, or engine where the power strokes are made to rapidly succeed each other. 75

From the foregoing it will be seen that on the intake stroke of either high pressure piston, air from the pipe O will enter the gasoline pipe near the discharge aperture of the latter, and will pass out through said aperture in admixture with the liquid fuel in a substantially atomized condition. This rich mixture of air and fuel being discharged into air supply pipe K³, through which air is passing to the engine intake, will be thereby diluted to form a combustible mixture of the proper character for use in the high pressure or combustion cylinders. It is to be noted that the primary current of air passing through pipe O and the secondary current passing through pipe K³ are both caused to travel by a common impelling 95 means which, in this specific embodiment of the invention, is the compressor. It should also be observed that not only are the fuel and atomizing air maintained at superatmospheric pressure, but also that the body 100 of air which receives the rich mixture thus attained is also at a pressure above that of the atmosphere.

Turning now to the flow regulating or constant level device, which, as stated, may 105 be interposed between tank M' and the nozzle device O'', this regulating device is shown in Figs. 6 and 8 as comprising a covered reservoir N⁴ into the top of which leads gasoline pipe O' from the supply tank M'. 110 From said reservoir an extension of pipe O' (seen at the left of the tank in the drawings) conducts fuel in regulated amounts to the nozzle device O'' above described. The reservoir is provided with a float controlling 115 an arm Q' which is pivoted on link Q³ and which carries a stop valve Q'', said valve being arranged to close the inlet end of pipe O when the level of liquid fuel in the tank has reached a predetermined height. This predetermined level is somewhat below that of the discharge aperture of nozzle device O'', the difference in level being, however, somewhat exaggerated in the diagrammatic showing of Fig. 8. An overflow pipe is 120 shown at R having an aperture above the liquid level as indicated. A drain pipe R' connects the bottom of the reservoir with the overflow pipe R, which may have a drain connection (not shown) to the supply tank 130

M'. The supply pipe O' and drain pipe R' are provided with valves R³, R² respectively. An arm upon each valve stem is connected to the link R⁴, to which is pivoted one 5 end of lever R⁵, the lever being fulcrumed, as at R⁶. At the other end of the lever is a notch R⁷, which is adapted to be engaged by a finger R⁸ attached to pendulum R⁹, which latter is pivoted to a reciprocating part of 10 the engine A¹², as shown. The moving system connected with the valve is provided with a spring r working in opposition to finger R⁸. A retarding device, such as a dash pot r', provided with a plunger r'' is 15 attached to the moving system by arm r³, which is connected to the stem of valve R³. The spring r tends constantly to rotate the valves to the right to close O' and open R', this motion, however, being slow because of 20 the dash pot r'. When the engine is operating normally, however, the finger R⁸ repeatedly engages the notch R⁷ and maintains the valve in the position shown in Fig. 25 6. The arrangement is such that the finger R⁸ engages lever R⁵ only when the engine is operating, refusing it when the engine is at rest or running slowly. By means of the arrangement just described, the small supply 30 of liquid fuel contained in the reservoir N⁴ is automatically drained from the reservoir when the engine stops, and the supply of fuel to said reservoir is also cut off.

During the normal operation of the engine, liquid fuel is supplied to the reservoir N only as fast as the supply in said reservoir is depleted by the requirements of the engine.

In order to dispose of fumes due to leakage of volatile fuel from the flow controlling device, or its connections, I provide a 40 fume collecting casing N'' or deodorizer which surrounds the fuel conducting and controlling mechanism and from which leads conduit N⁶ to the intake N of the compressor. This hood or casing has an opening at the top through which air is drawn to supply the engine, said opening being relatively remote from the point at which the hood is connected to the conduit N⁶. Consequently air drawn in through said opening 45 circulates around the inclosed fuel controlling mechanism as indicated by the arrows, rapidly evaporating and carrying off whatever small quantities of such fuel as may have escaped from the cocks, etc., and passing thence either directly or indirectly to the air induction passage or port K³ on its way to the engine intake. It will be readily understood that the deodorizer N'' could be connected to the induction port K³ of the engine instead of to the induction port of the pump or compressor as here shown. The movement of the air to the combustion chambers D³ and D⁴ would in such case be produced by the movement of the pistons in said 50 55 60

chambers. In other words, when the deodorizer is connected directly to pipe K³ the withdrawing action of the pistons D and D' is utilized to move the air to the chambers D³ and D⁴. 70

Fig. 8 shows diagrammatically an arrangement which may be used for operating the hit-or-miss mechanism controlling valve P, as well as for operating similar mechanism controlling valve R'' and R³. According to this arrangement an eccentric A¹³ on the engine shaft drives rod A¹⁴, thereby oscillating a lever A¹⁵ which is pivoted by means of link A¹⁶ to stationary support A¹⁷. Rod A¹⁸, pivoted to the upper arm of the 80 lever, reciprocates member A¹⁹, which is arranged to slide on bracket or ways A¹⁹, and thereby to actuate the mechanism comprising parts P³, P⁴, P⁵, etc., as above described. Rod A²⁰, pivoted to the other arm of the lever, reciprocates member A¹², which is arranged to slide on bracket or ways A²¹ and to actuate the device comprising parts R³, R⁹, etc., whose operation has also been explained above. Eccentric A¹³ is so disposed angularly on the shaft, and the relation and arrangement of the valve operating parts actuated thereby is such, as to secure proper timing of the valves in question. 85 90 95

The general operation of the engine is sufficiently obvious from the foregoing description, but for the sake of clearness, the movements of the pistons will be traced through a complete cycle. Assuming the parts to be in the position shown in Figs. 1 and 2, and a combustible charge just to have been drawn into the cylinder D³ by piston D on its preceding stroke to the left, the pistons will move as follows: Phase 1: The pistons move to the right. The previously inhaled combustible charge is compressed in D³; hot, partially expanded combustion gases pass from cylinder D⁴ through opened valve J' and conduit J to the expansion cylinder; and these partially expanded gases drive low pressure piston C toward the right. Phase 2: The compressed charge in D³ is ignited, driving piston D to the left on its working stroke, and combustible charge is drawn into cylinder D⁴ by the receding piston D'; low pressure piston C drives out the low pressure exhaust through exhaust valve K'. Phase 3: With the pistons again moving to the right, partially expanded combustion gases are transferred from cylinder D³ to the low pressure cylinder, where they drive the low pressure piston; the charge previously drawn into cylinder D⁴ is compressed by piston D'. Phase 4: The compressed charge in cylinder D⁴ is ignited, driving piston D' to the left on its working stroke. The combustible charge enters cylinder D³ as the piston D' recedes and the low pressure piston drives the low pressure exhaust out through valve K' as be- 100 105 110 115 120 125 130

fore, the parts now being again in the position assumed at the beginning of phase 1.

The operation of the other parts of the engine has been fully explained in connection with the detailed description of said parts and need not be repeated.

What I claim is:

1. In a combustion engine, the combination, with a combustion chamber of a liquid fuel supply tank, means whereby the fuel may be mixed with an air supply to form the combustion charge, a hood or casing inclosing at least a part of such mixing means and in communication with the atmosphere, and conduit means connecting the interior of said casing with said supply tank and with said combustion chamber, whereby air may pass through said casing and over the liquid in the supply tank to said combustion chamber.

2. In a combustion engine, the combination, with a combustion chamber, of an air passage leading to said chamber, a supply tank affording a supply of liquid fuel under fluid pressure, conduit means arranged to conduct fuel from said supply tank and discharge the same into said air passage, means located in said conduit, means for establishing and maintaining a substantially constant level of the liquid fuel prior to entry thereof into the air passage, such level being below that at which the fuel is discharged into said air passage, and an air supply inlet opening into said air passage, and a common means for producing super-atmospheric pressure for causing air to pass through both said air supply passage and said air supply inlet.

3. In a combustion engine, the combination, with a combustion chamber, of an air induction passage leading thereto, a liquid fuel supply tank, a fuel-feeding nozzle arranged to deliver fuel into said air passage, conduit means connecting said supply tank with said nozzle, a device located in said conduit means intermediate said tank and nozzle for regulating flow of liquid from the tank, and a casing inclosing said device and connected to said induction passage, said casing being open to the atmosphere at a point remote from its connection to the induction passage.

4. In a multi-cylinder heat engine having a common air induction passage for the cylinders, the combination with liquid fuel controlling devices for the engine, of a casing at least partially inclosing the fuel controlling devices and means of communication between the casing and said induction passage, whereby the engine may draw air through and from the casing.

5. In a heat engine having an air induction passage, the combination with a duct containing a liquid fuel under superatmospheric pressure, of fuel-controlling and feeding devices connected to said duct, a

casing at least partially inclosing the fuel controlling devices, and means of communication between the casing and the induction passage, whereby the engine may draw air through and from the casing.

70

6. In a multi-cylinder heat engine, the combination with liquid fuel controlling devices for the engine, of a casing for inclosing the fuel controlling devices, said casing having an air intake opening, and an air induction passage communicating with said casing at a point somewhat removed from said air intake opening and operatively connected to the charge intake of the engine, whereby the engine may draw air through 80 and from the casing.

75

7. In a combustion engine, the combination, with a combustion chamber, of means for supplying liquid fuel to said chamber, a hood or casing inclosing at least a part of such fuel-supply means and in communication with the atmosphere, and conduit means connecting the interior of said casing with said combustion chamber, whereby air may pass through said casing to said combustion 90 chamber.

85

8. In a four-cycle internal combustion engine, a liquid fuel supply tank, a combustion cylinder, a piston arranged to reciprocate therein, and mechanism arranged to supply 95 combustible mixture to said cylinder on the intake stroke of said piston, said mechanism comprising a fuel nozzle, an air conduit arranged to guide a fuel-entraining current of air into operative proximity to said nozzle, and another conduit arranged to supply air for diluting the rich mixture obtained by such entrainment prior to entry into said combustion cylinder, at least one of said air conduits being arranged to draw its air supply from said supply tank.

100

9. In a charge-forming apparatus for internal combustion engines, the combination, with fuel supply means, of an impelling means, for passing a current of air in proximity to said fuel supply means to form a mixture of fuel and air, both the said fuel and air being at super-atmospheric pressure and an additional body of air with which said mixture is diluted.

110

10. In a charge-forming apparatus for internal combustion engines, the combination, with fuel supply means, of impelling means for passing a current of air in proximity to said fuel supply means, both the said fuel and air being at super-atmospheric pressure, whereby a spray-like mixture of fuel and air is formed and maintained under pressure, and an additional body of air also under super-atmospheric pressure for diluting the 125 rich mixture thus attained.

115

11. In a combustion engine, the combination with a combustion cylinder having a charge intake and a piston reciprocable in said cylinder, of a main air supply passage 130

leading to said intake, a fuel feeding nozzle in said passage, an atomizing nozzle, a valve controlling said nozzles and means governing the operation of said valve and arranged 5 to cause said valve to reduce the feed of fuel from the nozzle at high speeds without affecting the main air supply.

In testimony whereof I have signed this specification in the presence of two subscribing witnesses.

ELMER A. SPERRY.
